BOTTLE WASHING MACHINE

Archie E. Ladewig and George F. Soelch,
Waukesha, Wis.Original application March 30, 1927, Serial No.
179,424. Divided and this application Febru-
ary 4, 1929, Serial No. 337,313

13 Claims. (Cl. 141—7)

The present invention relates in general to improvements in bottle cleansing machinery, and relates more specifically to improvements in the construction and operation of machines for automatically washing and rinsing milk bottles or the like.

An object of the invention is to provide a relatively simple and compact bottle washer wherein thorough cleansing of the bottles is assured, by automatically subjecting the bottles admitted to the machine to several washing and rinsing cycles before final discharge thereof. Another object of the invention is to provide improved mechanism for introducing the bottles into a washing machine. A further object of the invention is to provide improved mechanism for transporting a series of bottles through a washing machine or the like. Still another object of the invention is to provide improved mechanism for delivering the clean bottles from a washing machine. A further object of the invention is to provide improved means for initially rinsing, subsequently washing and finally draining the liquid from the bottles treated in an automatic washer. Another object of the invention is to provide improved automatic stop mechanism for bottle washing machines, whereby damage to the mechanism is avoided in case an abnormal condition arises. These and other objects of the invention will be apparent from the following description.

The present application is a division of application Serial No. 179,424 filed March 30, 1927, and some of the novel features disclosed but not specifically claimed herein, form the subject matter of said application or of another divisional application Serial No. 337,312, filed February 4, 1929, now Patent No. 1,906,974, granted May 2, 1933.

A clear conception of an embodiment of the invention and of the operation of a machine constructed in accordance with the improvement, may be had by referring to the drawings accompanying and forming a part of this specification in which like reference characters designate the same or similar parts in the various views.

Fig. 1 is a side elevation of an improved milk bottle washing and rinsing machine with a modified driving mechanism for automatically transporting the admitted bottles through the washing and rinsing cycle twice before delivering them from the machine.

Fig. 2 is a partly assembled front elevation

of the improved milk bottle washer, with a portion of the front casing broken away.

Fig. 3 is an enlarged fragmentary top view of one of the transverse bottle carrier frames.

Fig. 4 is an enlarged fragmentary front view of the carrier frame.

Fig. 5 is an enlarged fragmentary side elevation of the inlet and discharge end of the improved milk bottle washer having a portion thereof broken away.

Fig. 6 is a side view of the bottle supply and discharge mechanism showing the same in a different position of adjustment from that shown in Fig. 5.

Fig. 7 is an enlarged fragmentary side view of the improved bottle infeed slide.

Fig. 8 is an enlarged side view of one of the bottle carrier pockets showing the same positioned for the reception of a bottle from the infeed slide of Fig. 7.

Fig. 9 is a sectional view taken through the rear end of the main casing, showing the details of construction of the carrier adjusting guide or takeup.

Fig. 10 is a fragmentary sectional view through the main casing, also showing details of construction of the carrier adjusting guide.

Fig. 11 is an enlarged top view of the pump suction and filtering casing.

Fig. 12 is a part sectional side elevation of the pump suction and filtering casing.

Fig. 13 is an enlarged side elevation of a fragment of the automatic stop actuating mechanism.

Fig. 14 is an enlarged front elevation of the automatic stop mechanism.

Fig. 15 is a side elevation of the modified driving mechanism for automatically transporting the admitted bottles through the washing and rinsing cycle, twice before delivering them from the machine.

Referring specifically to Figs. 1, 2 and 5 of the drawings, the improved milk bottle washing machine comprises generally a main soaking, washing and rinsing casing 2 resting upon adjustable supports 10 and forming a housing for an intermittently movable endless series of bottle carrier pockets 3; and an auxiliary pre-rinsing casing 59 also resting upon supports 10 and associated with the front of the main casing 2, the casing 59 providing a support for the bottle supply and discharge mechanisms.

The lower portion of the main casing 2 provides a basin 27 for hot caustic soda or similar solution, and each of the side walls of the casing 55

2 is provided with an endless series of guide rails comprising lower horizontal rails 9 located below the liquid in the basin 27, upper rails 29, 22, located above the lower rails, an adjustable 5 curved rail 18 connecting the rear ends of each set of lower and upper rails, and a fixed curved rail 28 connecting the front ends of each set of lower and upper rails. The rear end rails 18 are interconnected by cross bars 100 as shown 10 in Figs. 9 and 10, and are swingable about lower pivots 68 by means of an adjusting screw 65, being guided near the top by means of pins 66 secured to the casing 2 and cooperating with slots 67 in plates secured to the rails. A plurality of plates 69 extend longitudinally of the machine between and beneath the lower rails 9, and between and rearwardly of the end rails 18, the plates 69 serving to retain the bottles within the inverted pockets 3. The forward portions 15 82 of the upper rails 29 are inclined for a considerable distance for the purpose of insuring complete drainage of liquid from the bottles prior to delivery thereof from the machine.

The endless series of bottle carrier pockets 3 25 are formed of wire, each pocket comprising a wire ring and a plurality of substantially straight wires extending laterally away from the ring and interconnected to provide a bifurcated bottom. A number of the individual pockets 3 30 are secured to each other as shown in Figs. 3 and 4, to form transverse groups, the ends of the carrier frames 23 being attached to end links 7. The successive links 7 are united by means 35 of pins with which the carrier rollers 8 are rotatably associated. The carrier rollers 8 engage the rail sections 9, 29, 18, 28, and the links 7 together with their pins, form an endless conveyor chain for the pockets 3. The machine 40 preferably embodies an odd number of groups of pockets 3, there being sixty nine groups or pockets to each endless series in the washer herein disclosed.

Located within the casing 2 above the basin 27 and between the lower and upper rails 9, 29, 45 is a series of reservoirs or basins 14, 15, 16 having headers provided with transverse rows of spray nozzles 30, 31, 32 of ordinary construction, located thereabove and adapted to deliver 50 cleansing liquid into the bottles as they advance along the horizontal portion of the upper rail 29 in inverted position. A downwardly and rearwardly inclined drainage plate 17 is disposed beneath the inclined rail portion 82 and spans the space between the side walls of the 55 casing 2, the plate 17 serving to return water from the draining bottles to the basin 16. The nozzles 30, 31 are supplied with suitable washing liquid by means of pumps 130, 131 respectively of well known construction, having their inlets 60 connected with suction casings 11, 63, and removable plates 64 permit inspection of the mechanism within the main casing 2. The suction casings 11, 63 are of like construction as shown in detail in Figs. 11 and 12. The side 65 wall 71 of the main casing 2 has openings therein which connect the basins 14, 15 with the casings 11, 63 respectively, some distance below the tops of the casings 11, 63. A filtering screen 70 divides each of the suction casings 70 11, 63 into a receiving compartment which is in open communication with the corresponding basin 14, 15, and a discharge compartment communicating with the pump inlet through a pipe 73. The screens 70 extend to the upper ends 75 of the casings 11, 63, and each of these casings

is provided with a drain 74 and with an overflow 72.

The bottle supply mechanism is clearly shown in Figs. 2, 5, and 6, and comprises a transverse group of bifurcated receiving pockets 20 movable 5 from upright to horizontal position and vice versa; a tilttable plate 44 movable from inclined to horizontal position and vice versa; and a series of push arms 40 and a simultaneously operable push bar 42 for ejecting the bottles from 10 the pockets 20 onto the plate 44 and for sliding other bottles from the plate 44 into the adjacent pockets 3. The receiving pockets 20 are oscillatable about a horizontal axis by means of a gear segment 50 which meshes with a gear segment 48. The segment 48 is secured to a transverse shaft 148 which is rockable by means of a bell crank 47 one arm of which is pivotally associated with a connection 46 and the other arm of which is likewise associated with a connection 52. The rear end of the connection 46 is pivotally associated with one arm of a bell crank 12 the other arm of which is provided with a roller cooperating with a groove in the cam 5. The tilttable plate 44 is oscillatable from 20 inclined position as shown in Fig. 5 to horizontal position in alinement with the pockets 20 as shown in Fig. 6 and vice versa, by means of a pair of levers 85 cooperating with links 51 secured to plate carrier arms 49. The plate 44 30 is preferably provided with a series of parallel fins or plates forming grooves for holding the bottles in proper position. The lower ends of the push arms 40 are adjustably attached to a cross bar 140 secured to actuating levers 39, and 35 the upper extremities of the push arms are movable through the bifurcations of the pockets 20. The cross bar 140 is operatively connected at its opposite ends with the push bar 42 by means of connections 41 and arms 141, the latter 40 of which are rigidly attached to the upper ends of the end levers 39.

A curved stop plate 45 having openings 81 through the lower portion thereof, extends along the path of travel of the rear end of the plate 45 44, and a pre-rinse supply pipe 80 has orifices 44, and therein formed to direct jets of water through the stop plate openings 81 and into the open ends of the downwardly tilted bottles resting upon the inclined plate 44. A resiliently supported guide plate 43 located at the upper end of the stop plate 45, is supported from the casing 59 by means of springs 57 and hinges 56, the tension of the springs 57 being adjustable by means of nuts 58, see Fig. 7. The guide plate 43 55 serves to properly admit the bottles regardless of their size, to the pockets 3, without breakage.

The bottle discharge mechanism is likewise clearly disclosed in Figs. 2, 5 and 6, and comprises a series of bottle ejectors 54 movable 60 through the pockets 3 while they are horizontally disposed; a series of bottle receiving and righting members 21; and a transversely movable final conveyor 19 of ordinary construction. The ejectors 54 are carried by a transverse rod 65 which is movable along arcuate slots 55 in the sides of the main casing 2, by means of levers 13 one of which coacts with a swivel block 38 as shown in Figs. 5, 6, 13 and 14. A bell crank lever 34 has one arm provided with a roller 70 cooperating with a groove in the cam 25, and has its other arm secured to an end of the bar 35 which extends freely through an opening in the block 38. Springs 36 embrace the bar 35 on opposite sides of the block 38 and engage ad- 75

justable nuts cooperating with the bar to vary the spring tension. A connection 37 has one end pivotally associated with the block 38, and has its opposite end attached to the lever 39 which actuates the push arms 40. The bottle receiving and righting members 21 are adapted to be swung about a horizontal pivot, from inclined position as shown in Fig. 5, to upright position as shown in Fig. 6, by means of a lever 53. The swinging end of the lever 53 is connected to an arm of the bell crank lever 47, by means of a connection 52.

The mechanism for driving the machine consists of an electric motor 4 mounted upon the main casing 2 and controllable by means of a switch 75. The motor 4 is connected through a flexible coupling 61, to a constantly rotating counter shaft which is interchangeably connectible by means of a manually operable jaw clutch 22, with high and slow speed gearing 62 of well known construction. The speed change gearing is operatively connected to cranks 83 in Figs. 1 and 15, or with cranks 60 as in Fig. 5, which cooperate through connections 84 with intermittent grip devices 6 comprising hooks 26 formed to grip and to advance the successive rollers 8 along the rails 28. Motion is also transmitted from the motor 4 through a driving chain 24 to a transverse counter shaft 33 to which the cams 5, 25 are secured. The switch 75 which controls the circuit of the motor 4, is also operable by means of automatic stop mechanism such as shown in Fig. 14. This mechanism comprises a latch 78 operable by abnormal displacement of the swivel block 38, a latch plate 77 mounted upon a pivot 90 supported by the casing 2 and cooperating with the latch 78, a spring 79 for swinging the latch plate downwardly about its supporting pivot 90 when the latch 78 is released, and a rod 76 connecting the plate 77 with the lever of the control switch 75.

While the carrier pocket advancing mechanism of Fig. 5 is adapted to intermittently advance the pockets a distance equal to the space between the axes of successive rollers 8, the mechanism of Figs. 1 and 15 is constructed to intermittently advance the pockets double this distance in order to cause the bottles to be transported twice through the machine before final discharge thereof. The cranks 83 and the grip devices 6 of this modified mechanism are formed to produce double the throw of the pawls or hooks 26 in the mechanism of Fig. 5, and such operation combined with the odd number of pockets 3 in each series, produces the desired result of causing the rinse spray nozzles 32 to cooperate only with alternate pocket rows just prior to final discharge of the washed bottles. With the machine properly designed, the cranks 83 and devices 6 may readily be substituted for the single throw cranks 60 and devices 6 of the machine disclosed in Fig. 5 at the option of the operator.

During normal operation of the machine, the dirty bottles are placed in the receiving pockets 20 when positioned as shown in Fig. 5, in substantially upright position while the motor 4 is operating continuously. Periodically, the pockets 20 are swung rearwardly to horizontal position as shown in Fig. 6 whereupon the push arms 40 are moved through the bifurcations of the pockets 20 and eject the dirty bottles therefrom onto the plate 44 with their open ends pointing toward the machine. After the bottles have been thus positioned upon the plate 44, the

pockets 20 are returned to bottle receiving position as shown in Fig. 5, and the plate 44 is tilted downwardly thereby causing the bottles to slide toward the openings 81 in the stop plate 45 and to receive the full force of the pre-rinsing jets 5 discharged from the pipe 80. The plate 44 is eventually again returned to horizontal position as shown in Fig. 6, whereupon the push bar 42 becomes effective to slide the pre-rinsed bottles from the rear end of the plate 44 over the guide 10 plate 43 and into the horizontally disposed group of pockets 3 positioned with respect to the plate 43 as shown in Figs. 7 and 8. Simultaneously with the removal of the pre-rinsed bottles by the bar 42, the push arms 40 are 15 ejecting other dirty bottles from the pockets 20. The intermittent grip device 6 urges the loaded bottles 3, step by step, along the successive rails 28, 9, 18, 29, 82. As the bottles travel through the basin 27, they are subjected to the soaking 20 and washing action of the hot caustic soda solution. While travelling along the end rail 18, the bottles are inverted and the caustic soda solution is delivered therefrom into the basin 27. The bottles are subsequently subjected to jets 25 of washing and rinsing liquid delivered from the nozzles 30, 31, 32 during their travel along the rails 29 and over the basins 14, 15, 16. When the double throw cranks 83 of Figs. 1 and 15 are used, the pawls 26 cooperate with the 30 rows of pockets 3 and with the several spray means, to cause the washing liquid sprays from the nozzles 30, 31 to be delivered against the interiors of all of the bottles while traversing the upper conveyor stretch, and to cause the 35 rinsing liquid sprays from the nozzles 32 to be delivered only against alternate pocket rows which have passed through the machine two successive times, thus insuring thorough washing and final rinsing. When passing over the 40 inclined rail sections 82, the bottles are tilted thus causing the liquid remaining therein to flow toward the lower inner side surfaces thereof and to be quickly and effectively drained from the inverted bottles, the drainage liquid returning 45 to the basin 16 along the drain plate 17. The pockets containing the finally washed and rinsed bottles are eventually again brought into horizontal position at the front of the machine, whereupon the ejectors 54 are brought forward 50 through the bottoms of the pockets 3 and push the clean bottles from the pockets upon the members 21, while these members are positioned as shown in Figs. 1 and 5. The members 21 are subsequently swung forward to upright 55 position thereby setting the clean bottles upon the chain conveyor 19 which delivers them from the machine.

If an abnormal condition of operation such as 60 improper insertion of a bottle, arises, the automatic stop mechanism of Figs. 13 and 14 becomes effective to throw the switch and to stop the motor 4, thereby avoiding damage to the wire pockets and other relatively frail parts of the machine. This stop becomes effective if the 65 normal movement of the swivel block 38 is obstructed in any manner, thereby causing the latch 78 to release the latch plate 77 and permitting the spring 79 to become effective to throw the switch. For example, if the forward 70 motion of the ejector 55 and of the arms 13 which carry the same, is interrupted as by one or more bottles becoming jammed within the carrier pockets 3, and the bell-crank 34 to which the rod 35 is attached, continues to move, the 75

latch 78 will automatically be released from the plate 77 to thereby stop the machine until the jammed bottles have been removed.

From the foregoing description, it will be apparent that the bottles are automatically successively pre-rinsed, washed, finally rinsed, and removed from the machine at the loading end thereof. By pre-rinsing the dirty bottles, the liquid in the basin 27 may be maintained relatively clean for a long period of time. The pump suction casings 11, 63 and the strainers therein, insure a relatively clean supply of liquid for the nozzles 30, 31, and the inclined rail sections 82 provide for effective removal of water from the bottles prior to their delivery from the machine. The mechanism of Fig. 15 cooperating with odd numbered series of pockets 3, permits automatic application of a double wash without reducing the capacity of the machine, and the drain plate 17 besides conducting the drainage liquid to the reservoir 16, prevents the fumes from the basin 27 from reaching the motor and gearing. The machine while being relatively simple and compact, has large capacity and the adjusting mechanism associated with the rear rails 18 enables maintenance of proper tension in the carrier chain. The intermittent grip mechanism eliminates necessity of using noisy sprockets, and the supply and discharge mechanisms operate to avoid breaking bottles. The self adjusting feed plate 43 insures proper admission of the bottles to the pockets 3, irrespective of the size, and the pockets 3 may be readily formed at low cost, of standard wire.

It should be understood that it is not desired to limit the invention to the exact details of construction and operation herein shown and described, for various modifications within the scope of the claims may occur to persons skilled in the art.

It is claimed and desired to secure by Letters Patent:—

1. In combination, an intermittently driven endless conveyor having an odd number of successive rows of bottle carrier pockets forming superimposed oppositely moving stretches along which bottles are successively transportable, a casing forming a liquid basin through which the bottles are carried by the lower conveyor stretch, spray means cooperable with all pocket rows for delivering washing liquid against the interior of all bottles while traversing one portion of the upper conveyor stretch, other spray means cooperable during the same conveyor cycle only with alternate pocket rows during periods of rest of the conveyor for delivering rinsing liquid against the interior of the bottles carried by said rows while traversing still another portion of said upper conveyor stretch, and means for actuating said conveyor to successively advance said pockets by steps equal to twice the distance between rows so as to subject the bottles to initial soaking, to the action of said washing spray means, to final soaking, and to the action of said washing spray means and said rinsing spray means.

2. In combination, an intermittently driven endless conveyor having an odd number of successive rows of bottle carrier pockets forming lower and upper portions along which bottles are successively transportable, a casing forming a liquid basin through which the bottles are carried by the lower conveyor portion, spray means cooperable with all pocket rows for delivering washing liquid against the interior of all bottles

while traversing one part of the upper conveyor portion, other spray means cooperable during the same conveyor cycle only with alternate pocket rows during periods of rest for delivering rinsing liquid against the interior of the 5 bottles carried by said rows while traversing another part of said upper conveyor portion, and means for actuating said conveyor to successively advance said pockets by steps equal to twice the distance between rows so as to subject the bottles to initial soaking, to the action of 10 said washing spray means, to final soaking, and to the action of said washing spray means and said rinsing spray means.

3. In combination, a casing having a soaking 15 liquid basin in the lower portion thereof, means forming a washing liquid receiving basin within said casing directly above said soaking liquid basin, an endless series of bottle carrier pockets movable in succession through said soaking liquid basin and over and beyond said washing liquid receiving basin, and a substantially plane drain plate above the portion of said soaking liquid basin beyond said washing liquid receiving basin, all portions of said drain plate being 20 inclined rearwardly and downwardly toward said washing liquid receiving basin so as to prevent drainage of liquid into said soaking liquid basin.

4. In combination, a casing having a series of 30 rails forming an endless track with upper and lower portions, an endless series of bottle carrier pockets movable along said track, bottle washing means including a liquid reservoir located in said casing within said pocket series, and a 35 drain plate within said series beyond said washing means, said drain plate being inclined downwardly toward said liquid reservoir and said track having a rail section also inclined downwardly toward said reservoir located above said plate. 40

5. In combination, a casing having a soaking liquid basin in the lower portion thereof, means forming a washing liquid receiving basin above said soaking basin, bottle carrier pockets movable in succession through said soaking liquid 45 basin and over and beyond said washing liquid receiving basin, and a substantially plane drain plate above the portion of said soaking liquid basin beyond said washing liquid receiving basin, all portions of said plate being inclined down- 50 wardly in the same direction toward said washing liquid receiving basin so as to prevent escape of washing liquid into said soaking liquid basin.

6. In combination, a casing having rails forming an endless track with upper and lower por- 55 tions, an endless series of bottle carrier pockets movable along said track, bottle washing means including a liquid reservoir disposed within said casing above the lower portion of said track and of said pocket series, and a drain plate disposed 60 between the upper and lower portions of said track and of said pocket series adjacent to said washing means, said plate being inclined downwardly toward said reservoir and said track having a section similarly inclined toward said 65 reservoir so as to prevent precipitation of washing liquid upon said lower track and pocket series portions.

7. In combination, a casing having therein rails forming an endless track with upper and lower 70 portions and also a soaking liquid basin in the lower portion thereof, an endless series of bottle carrier pockets movable through said basin and along said track, bottle washing means includ- 75 ing a liquid reservoir disposed within said casing

- above said basin and between said upper and lower track portions, and a drain plate disposed above said basin beyond said reservoir and between said track portions, said plate being inclined downwardly toward said reservoir and said upper track portion having a section similarly inclined toward said reservoir so as to prevent precipitation of washing liquid into said soaking basin.
10. 8. In combination, a casing having therein an endless track with upper and lower portions and a soaking liquid basin near which the lower track portion is disposed, bottle washing means including a liquid reservoir disposed between said upper and lower track portions, an endless series of bottle carriers movable along said track through said basin and in proximity to said washing means, and a drain plate extending away from said reservoir between said track portions, said plate being inclined downwardly toward said reservoir and said upper track portion having a similarly inclined section above said plate so that all liquid discharged from bottles being transported by carriers traversing said track section will be returned by said plate to said reservoir.
15. 9. In combination, a casing having therein an endless track with upper and lower portions and a soaking liquid basin along which the lower track portion extends, bottle washing means including a liquid reservoir and spray means above the reservoir disposed between said upper and lower track portions, an endless series of bottle carriers movable along said track through said basin and in proximity to said spray means, and a drain plate extending away from said reservoir in the direction of travel of the bottles and between said track portions, said plate being inclined downwardly toward said reservoir and said upper track portion having a similarly inclined section above said plate so that all liquid discharged from bottles being transported by carriers traversing said track section will be returned by said plate to said reservoir.
20. 10. In combination, a casing having therein a track with upper and lower portions and a soaking liquid basin adjoining the lower track portion, bottle washing means including a liquid reservoir disposed between said upper and lower track portions, a series of bottle carriers movable along said track through said basin and in proximity to said washing means, and a substantially plane drain plate extending beyond said reservoir between said track portions, all portions of said plate being inclined downwardly toward said reservoir and said upper track portion having a similarly inclined section above said plate so that liquid discharged from bottles being conveyed over said track section will be returned by said plate to said reservoir.
25. 11. In combination, a casing having therein a track with upper and lower portions and a soaking liquid basin adjoining the lower track portion, bottle washing means including a liquid reservoir disposed between said upper and lower track portions, a series of bottle carriers movable along said track through said basin and in proximity to said washing means, and a drain plate extending beyond said reservoir between said track portions, all portions of said plate being inclined downwardly toward said reservoir and said upper track portion having a similarly inclined section extending along and above said plate so as to prevent precipitation of liquid discharged from bottles traversing said section into said soaking basin.
30. 12. In combination, an intermediately driven endless conveyor having an odd number of successive transverse rows of bottle carrier pockets forming lower and upper conveying portions along which bottles are successively transportable, means forming a liquid basin through which the bottles are transported by the lower conveyor portion, multiple rows of spray means cooperable with all pocket rows for delivering washing liquid against the interior of the bottles while traversing one part of the upper conveyor portion, other spray means cooperable during the same conveyor cycle only with alternate pocket rows during periods of rest for delivering rinsing liquid against the interior of the bottles carried by said rows while traversing another part of said upper conveyor portion, and means for actuating said conveyor to successively advance said pockets by steps equal to twice the distance between successive pocket rows so as to subject the bottles to initial soaking, to the action of said washing spray means, to final soaking, and to the action of said washing spray means and said rinsing spray means.
35. 13. In combination, an intermittently driven endless conveyor having an odd number of successive transverse rows of bottle carrier pockets forming lower and upper conveying portions along which bottles are successively transportable, means forming a liquid soaking basin through which the bottles are transported by the lower conveyor portion, multiple rows of spray means cooperable with all pocket rows for delivering washing liquid against the bottles while traversing one part of the upper conveyor portion, other spray means cooperable during the same conveyor cycle only with alternate pocket rows during periods of rest of the conveyor for delivering rinsing liquid against the bottles carried by said pocket rows while traversing another part of said upper conveyor portion, and means for actuating said conveyor to successively advance said pocket rows so as to subject the bottles to initial soaking, to the action of said washing spray means, to final soaking, and to the action of said washing spray means and said rinsing spray means.
